STUART PARMELEE MILLER, OF TENAFLY, NEW JERSEY, ASSIGNOR TO THE BARRETT COMPANY, OF NEW YORK, N. Y., A CORPORATION OF NEW JERSEY

DISTILLATION OF TAR

Application filed April 13, 1927. Serial No. 183,263.

This invention relates to improvements in the distillation of tars, and particularly to the utilization of the heat available in the gases produced in coal-carbonization plants to distill tar and to produce oils and pitches by such distillation. The invention will be described especially with reference to its application to coke ovens.

In the ordinary operation of by-product coke ovens the gases produced by the coking operation pass from the individual ovens through uptake pipes and goose-necks to a collector main common to the ovens of the battery. The gases, commonly known as "foul" gases, leave the ovens at high temperature, e. g., 600° to 700° C. or higher, and carry a considerable proportion of volatilized tars and oils as well as entrained tarry matter and coke and coal dust. Ordinarily the gases are cooled as rapidly as possible by the application of sprays of ammonia liquor or ammonia liquor and tar in the goose-necks and collector main, the heat in the gases being thereby dissipated and lost. The rapid cooling causes separation of tar containing heavier oils in the collector main. Further cooling is effected in the cross-over main which connects the collector main to the condensing system and in the condensing system, and an additional quantity of tar carrying both heavier and lighter oils is thus separated. The collected tar in many cases is shipped from the coke-oven plant to a tar-distillation plant for distillation and separation of the oils and the production of pitches of varying qualities. Handling losses, freight charges and distillation costs, including fuel and capital and maintenance expenses for the special equipment required for distillation, add to the cost of production of the tar-distillation products.

It is the object of the present invention to provide a method which permits the distillation of tar at a coke-oven plant, the utilization of the heat of the coke-oven gases for that purpose, and particularly the enrichment of the gases in oil vapors and the production of pitches having the various qualities and characteristics required by the trade.

According to the present invention the heat

of the coke-oven gases as they come from the coke ovens is utilized to distill tar and to separate vaporizable oils therefrom by spraying or otherwise bringing the tar into intimate contact with the hot coke-oven gases. 55 The heat carried by these gases is greatly in excess of the amount of heat required to distill all of the tar produced by the coke-oven battery. The present invention is designed particularly to utilize only a portion of this 60 heat, that is to say, the heat carried by the so-called "lean" gases. These "lean" gases are withdrawn from the coke ovens during the latter part of the coking operation. At this stage the amount of tar contained in the 65 gases is relatively low and this tar is relatively high in insoluble matter as compared with the tar contained in the gases given off during the early stages of the coking operation. There is no sharp line of division between rich and 70 lean gases. Under ordinary conditions the gases leaving the ovens during the first half of the coking cycle may be regarded as rich,—that is, containing relatively large amounts of tarry matter. The ratio of rich to lean gas 75 may, of course, be varied widely to suit any particular set of conditions on distillation.

By utilizing these "lean" gases to distill tar the gases are enriched in condensable oil vapors which may be recovered therefrom by 80 suitable condensation. The lean gases, being relatively free from tar constituents, are particularly desirable for the distillation and recovery of oils from tar or oils since upon condensation they yield such oils substantially free from tar and suitable, therefore, for immediate use for the various purposes for which such oils are adapted.

Good operation of by-product coke ovens requires that the temperatures throughout the 90 block be maintained uniform. Therefore, coke-oven operators have devised systems of rotation for discharging and charging of the ovens which for any individual oven will affect the temperature of the block as little 95 as possible. An example of the discharging and charging schedule is given below. It is assumed that the coke-oven battery consists of sixty ovens operating on a twenty-hour coking cycle per oven. Satisfactory tempera- 100

tures throughout the block may be maintained if the ovens are, as regards discharging and charging, divided into groups of ten ovens each. It is then required that within each 5 ten-oven group the discharging and charging of the ovens be rotated in such a manner as to maintain uniformity of temperature within the group. Each oven is discharged and charged every twenty hours. Therefore, in 10 a ten-oven group, an oven will be discharged and charged every two hours.

The numbers below illustrate a complete cycle for a group of ten ovens. The Roman numerals indicate the serial numbers of the 15 individual ovens; the Arabic numerals indicate the order in which the individual ovens are discharged and charged, assuming for this example that No. I oven has just been discharged and charged.

20

	I	II	III	IV	V	VI	VII	VIII	IX	X
Cycle 1....	1	4	7	10	3	6	9	2	5	8
Cycle 2....	11	14	17	20	13	16	19	12	15	18

25 It will be understood by those skilled in the art that the ovens in the first group of ten must be synchronized with those in the second group of ten, and so on, so that the temperatures throughout the entire battery are 30 uniform. At the completion of one cycle the number I oven has completed the distillation operation and is ready to be discharged and recharged with coal. Consequently in the group of ten ovens, certain of the ovens will 35 be operating in the initial phase of the distillation operation; others will be in an intermediate stage and others will be approaching completion of the distillation. Assuming oven No. I to be freshly charged, the gases 40 from ovens III, X, VII, IV and I will be rich, and those from ovens VIII, V, II, IX and VI will be lean. Two hours later, however, the ovens delivering rich gas will be V, VII, IV, I and VIII, and those delivering lean gases 45 will be V, II, IX, VI and III. It will be evident to those skilled in the art that with this system of rotation of ovens, from the ten ovens in series at least two, and in some cases three or four of the ovens, will be delivering 50 lean gas simultaneously.

If, therefore, only a limited amount of tar distillation is to be carried on as, for example, the distillation of the tar produced by the coke-oven battery, it may be sufficient to utilize only the lean gases from the first ten ovens of the battery at the appropriate time in the operation thereof. Thus, gases from at least two of the ovens of the first series can be employed for tar distillation, the gases from the selected ovens being directed at the appropriate time through suitable distillation apparatus in which the heat of these gases is utilized for the purpose of distillation. The 60 gases from the remaining ovens of the se-

ries, being relatively rich in oil constituents during the initial stage of coal distillation, will be directed into the ordinary collector main and mingled with gases from the remaining ovens of the battery.

70 Of course, where more distillation is to be effected the gases from a second series of ten ovens can be utilized similarly and if desired all of the ovens of the battery can be so connected to the distillation apparatus as to deliver lean gases at the appropriate time there- 75 to for the purpose of distilling tar, the ovens being connected at other times to the collector main in which the gases are cooled in the usual manner by the application of ammonia liquor or ammonia liquor and tar. Thus, tar from 80 sources other than the battery can be distilled by utilizing the lean gases therefrom and such lean gases can be enriched in oil con-

85

stituents which can be recovered subsequent- 90 ly by condensation.

In carrying out the invention the intimate contact between the hot lean gases and the tar to be distilled is accomplished preferably by spraying the tar into a suitable still in which the tar is subjected to the relatively high temperature of the gases for the purpose of vaporizing and separating the vaporizable oil constituents of the tar. The distillation can be conducted, for example, in an auxiliary 100 collector main connected to the uptake pipes through which the gases are withdrawn from the ovens. The auxiliary collector main may be provided with spray nozzles for the introduction of the tar to be distilled in the 105 form of a finely divided spray. The partially distilled tar or pitch resulting from contact of the tar with the hot lean gases can be withdrawn intermittently or continuously from the auxiliary collector main. It may be 110 utilized after a single distillation operation as described or it may be recirculated through the auxiliary collector main for further distillation and separation of oil constituents.

115 The invention can be applied without substantial change in the equipment and arrangement of an ordinary by-product coke-oven battery. Thus, the gases produced in the earlier stages of the distillation in the respective ovens can be delivered to the ordinary collector main and subjected therein to cooling with ammonia liquor or ammonia liquor and tar to separate tar constituents from the gases. These gases may be conducted thereafter through the usual cross-over main wherein they may be further cooled and delivered thence to the ordinary condensers in which they are subjected, for example, to direct cooling with ammonia liquor for the 120 125 130

purpose of separating tar and oil constituents. The tar and ammonia liquor withdrawn from the collector main, the cross-over main and condensers can be separated in suitable decanters and the ammonia liquor can be treated for the recovery of ammonia therefrom and utilized for further cooling of the hot coke-oven gases. The tar recovered may be distilled in the manner hereinbefore described to separate and recover vaporizable oil constituents and to produce pitches of the desired consistency.

In carrying out the invention the desired number of ovens may be connected through separate uptake pipes to the separate or auxiliary collector main, valves being provided to permit the diversion of the hot gases either through the usual uptake pipes to the collector main or into the uptake pipes leading to the auxiliary collector main. During the initial and intermediate stages of the coal distillation the hot coke-oven gases will pass into the collector main as in the usual operation. By operating the valves the lean gases produced in the latter stage of distillation will be diverted from the selected ovens in which coal distillation is nearing completion into the auxiliary collector main and while such lean gases are passing through the auxiliary collector main the latter will be supplied with tar to be distilled through the spray nozzles provided for that purpose. The lean gases will thus heat and distill the tar and the oil vapors separated from the tar will be carried away with the lean gases which are thereby enriched in oil constituents. The partially distilled tar or pitch will flow into the bottom of the auxiliary collector main and will be withdrawn therefrom for use as pitch or it may be recirculated or otherwise subjected to further distillation for the purpose of producing harder pitches and to recover additional quantities of oil vapors.

The distillation of tar in the auxiliary collector main may be accomplished in a variety of ways involving the intimate contact of the tar with the gases therein. Preferably the introduction of ammonia liquor to the auxiliary collector main is avoided except as hereinafter described and in place thereof the main is flushed with a sufficient quantity of tar or oil or tar and oil to ensure against any accumulation of heavy pitch in the main. This object is readily accomplished if a sufficient quantity of the flushing medium is provided and if the temperature is kept high because the heavy pitch if it is formed is soluble in the hot tar or oil used and any accumulation will be dissolved and carried along with the stream of hot tar which flows through the main. All or a portion of the tar can be introduced advantageously through spray nozzles provided for that purpose in the auxiliary collector main

and in the connected goose-necks. In addition to the tar or oil introduced through the spray nozzles in the collector main and goose-necks, tar or oil or mixtures thereof can be circulated through the main by introducing it at one end thereof and withdrawing it from the other. There are two important requirements, the first of which is the intimate mingling of the tar with the lean gases from the ovens at high temperature to effect the desired distillation and the other is the constant washing or flushing of the surfaces of the main with a large excess of hot tar or oil or mixtures thereof to prevent an accumulation thereon of heavy pitch. Both of these purposes can be accomplished by the use of spray nozzles. It can be accomplished likewise by the use within the main of suitable mechanical agitating devices actuated to maintain a constant and violent agitation of the tar as it flows through the main so that the tar is splashed or thrown into the stream of coke-oven gases and onto the exposed surfaces of the main.

The agitation can be effected by the use of a rotating shaft or shafts with suitable paddles thereon. Similarly rotating cones or other agitating and splashing devices may be disposed in the collector main and arranged to be actuated for the purpose of throwing the tar into the stream of gases and upon the exposed surfaces of the main. Discs, plates or spines on the rotating shafts will achieve the same purpose. The required agitation can be accomplished also by the introduction of compressed gases such, for example, as fuel or coke-oven gases or steam, through a suitable distributor pipe immersed in the tar, or suction T, (McDaniel type ejectors) may be located in the main with their suction ends beneath the level of the tar therein. If the nozzles of the ejectors are allowed to extend above the surface of the tar a spray of tar will be thrown up into the gases.

Although indiscriminate cooling of the gases in the auxiliary collector main is to be avoided it may be desirable to introduce water or ammonia liquor with the tar which is sprayed into the auxiliary collector main to cool the gases to a predetermined and regulated extent. The regulation of the cooling effect can be accomplished more readily with water because of the highest specific and latent heats of water as compared with tar and oils. It is possible, therefore, to add water or ammonia liquor in the proportion required to remove substantially all heat from the gases except that needed for the distillation of tar. When hard pitch is desired less water can be added.

The gases and vapors from the auxiliary collector main are preferably delivered to a condensing system independent of the ordi-

nary condensers in which the rich gases are cooled. Such an independent condensing system may include condensers designed to separate all of the oil constituents together or 5 fractional condensers may be employed to remove the oil constituents from the gases in separate fractions having different boiling points and adapted for various commercial uses. The oils recovered from the lean gases 10 will be substantially free from tar constituents and adapted, therefore for commercial use without further distillation or purification.

The amount of tar which can be distilled 15 by the hot gases from a single coke oven is many times that which the coke oven itself produces so that the lean gases from relatively few selected ovens of the battery will suffice to distill all of the tar produced by the 20 battery. It may be desirable, however, to utilize the heat from a greater number of ovens for the distillation of tar from other sources such as that produced by other coke ovens or from coal-distillation plants of 25 different kinds. By connecting a suitable number of uptake pipes to the auxiliary collector main an additional quantity of tar from any source can be distilled effectively and the lean gases can be enriched in oil constituents 30 which can be recovered subsequently for commercial use.

In carrying out the invention the tar may, as hereinbefore indicated, be brought into contact with the hot lean gases only once or it 35 may be recirculated and again passed through one of the auxiliary collector mains to effect a further distillation of the tar and the production of a harder pitch containing a higher percentage of "free carbon" or in 40 soluble matter. This further distillation can be effected by circulating the tar through the auxiliary collector main while the latter is being operated and supplied with lean gases from the ovens to which it is connected. 45 In such successive distillation of the tar, pitches of different consistency and having varying characteristics can be withdrawn and utilized as commercial products or subjected to further distillation as may be de- 50 sired.

The amount of distillation effected in the auxiliary collector main can be regulated as desired by varying the quality of the tar introduced, the time during which it is permitted to remain in contact with the hot coke-oven gases, and by modifying various other factors which affect the rate of distillation. It is possible thus to produce distillates, tar or pitch having the desired characteristics by 55 the operation of the collector main as hereinbefore described.

The invention is of more or less general application to different types and constructions of by-product coke ovens such as Semet-Solvay ovens, Koppers ovens, etc., but it will 60

be described more particularly in connection with by-product coke ovens of the Semet-Solvay type.

In the accompanying drawings, in which an apparatus suitable for the practice of the 70 invention is disclosed,

Fig. 1 is a plan view of a portion of a coke-oven battery illustrating the application of the invention thereto;

Fig. 2 is a side elevation of the structure 75 as illustrated in Fig. 1; and

Fig. 3 is an enlarged sectional view of the auxiliary collector main and connections.

Referring to the drawings, 5 indicates a battery of ovens which are connected by uptake pipes 6 and goose-necks 7 to a collector main 8. The latter may be provided with spray nozzles in the usual manner for the introduction of ammonia liquor or ammonia liquor and tar for the purpose of cooling the 85 gases therein. The collector main is connected to a cross-over main 9 which delivers the gases to condensers 10 wherein they are subjected to further cooling, for example, with ammonia liquor, for the purpose of condensing 90 and separating the oil constituents. The gases may pass thence to an exhauster 11 which maintains the pressure balance in the system. Thereafter the gases may be treated in the usual manner for the recovery 95 of light oils and other valuable constituents, the gases being delivered finally to a suitable gasometer for storage as fuel gases. The ammonia liquor and tar from the collector main, cross-over main and condensers may be 100 delivered to decanters 12 and 13 in which the tar is separated from the ammonia liquor. The latter may be treated in any suitable way to recover ammonia therefrom. The tar can be delivered to a tank 14 where it is 105 stored for subsequent distillation in accordance with the invention.

A suitable number of the ovens, for example, the first ten, may be provided with separate uptake pipes 15 preferably at the 110 rear of the ovens and communicating with a separate or auxiliary collector main 16 wherein the tar is distilled. The gases are permitted to pass from the ovens into the auxiliary collector main only during the lat- 115 ter part of the coal-distillation operation when the gases are relatively low in tar constituents. At the proper time, as indicated by the period of operation, the lean gases are diverted from the ordinary collector main 120 into the auxiliary collector main and tar is supplied then through the spray nozzles 17 through pipes 18 from a source of supply such as the tank 14, a pump 19 being provided to force the tar through the spray nozzles. 125 The pitch can be withdrawn from the auxiliary collector main through a pipe 20 and all or a portion thereof can be recirculated by means of a pump 21 through a pipe 22 which is connected to the spray nozzles or through 130

a pipe 23' which delivers the pitch to the end of the collector main. Thus, the pitch may be subjected to further heating and distillation in the auxiliary collector main to produce harder pitches and to remove more of the volatile constituents therefrom.

The lean gases carrying the vaporizable oil constituents of the tar pass through a pipe 24' into condensers 23 which, for example, may be arranged in series and may be designed to remove the vaporizable constituents in fractions so as to permit the recovery of a number of oil products having different boiling points. The gases escaping from the condensers may be delivered through a pipe 24 to the exhauster 11, being mingled with the gases from the remaining ovens of the battery and subjected to treatment for the recovery of light oils and other valuable constituents before the gases are finally discharged from the system.

The invention as described permits the distillation of tar in an economical and satisfactory manner to produce pitches having the desired characteristics and to recover valuable oil constituents from the tar. The oils recovered, being substantially free from contaminating tar constituents, may be employed directly without further distillation or purification. The invention may be utilized likewise for the distillation and purification of dirty oils, that is to say, oils which are contaminated with tar constituents, such constituents being separated and retained in the distillation apparatus.

While I have described the preferred mode of operation according to the invention, it is to be understood that various changes may be made in the procedure as described without departing from the invention or sacrificing any of the advantages thereof.

I claim:—

1. The method of distilling coal tar and of producing pitch and distillate oils therefrom and from coal distillation gases, which comprises distilling coal, drawing off lean gases relatively low in tarry constituents given off during the latter part of the coal distillation operation separately from rich gases given off during the earlier portion of the coal distillation operation, bringing the lean gases while still at a high temperature into direct and intimate contact with the tar in regulated amount to effect distillation of the tar and the production of a pitch residue and of distillate oils which are carried in vapor form in the lean gases, and subjecting the admixed gases and vapors to cooling to condense oils therefrom.

2. The method of distilling coal tar and of producing pitch and distillate oils therefrom and from coal distillation gases, which comprises coking coal, drawing off lean gases given off during the latter part of the coking operation separately from rich gases given

off during the earlier portion of the coking operation, distilling the tar by atomizing it into the lean gases after they are collected and while they are still at a high temperature and regulating the amount of tar so sprayed and the volume of the hot gases to effect rapid distillation of the tar and the production of a pitch residue and of distillate oil vapors carried by the gases and scrubbing of the gases with the atomized tar, and cooling the resulting admixed gases and vapors to condense oils therefrom.

3. The method of distilling coal tar at coke oven plants and of producing pitch and distillate oils therefrom and from hot coke oven gases, which comprises coking coal, drawing off lean gases relatively low in tarry constituents given off during the latter portion of the coking period separately from rich gases given off during the earlier portion of the coking period and passing the lean gases while still hot through a still, atomizing tar to be distilled into the gases in the still and regulating the amount of tar brought into intimate contact with the gases with reference to the high temperature of the gases in the still so that the tar is rapidly distilled to produce pitch and distillate oils which are carried in vapor form by the gases, drawing off the resulting gases and vapors at a high temperature and cooling the same to condense oils therefrom.

In testimony whereof I affix my signature.
STUART PARMELEE MILLER.
